UNITED STATES PATENT OFFICE.

JACQUES MORAT, OF YONKERS, NEW YORK.

GRINDING MACHINERY.

1,110,222.

Specification of Letters Patent.

Patented Sept. 8, 1914.

Application filed November 18, 1910. Serial No. 593,067.

To all whom it may concern:

Be it known that I, JACQUES MORAT, a citizen of the Republic of France, residing at Yonkers, in the county of Westchester and State of New York, have invented certain new and useful Improvements in Grinding Machinery, of which the following is a specification.

My invention relates to an improvement in grinding machinery, whether adapted to be used for grinding sand, rock, chemicals, etc., and it pertains more particularly to the pan and roller type of machine, consisting as a rule of a circular pan revolving under two rollers by means of gear and shaft mechanism. In this general type of machines, the various substances constituting the mixture are thrown into the pan while the machine is in operation, and after it has run a brief period and the sand is mixed and ground properly, it is removed to make room for another charge. The rollers are usually heavy, and the wear at the face of these rollers and at the bottom of the pan is very great. In order to decrease the expense of renewing these wearing parts, it has been customary in some instances to fit the pans with removable plates for the bottoms of the pans, in order to save the pans, and the rollers themselves have been provided with detachable rims; moreover the detachable rims and removable plates have been made of hard iron or steel, such as manganese steel. But in all instances, the abrading surfaces wear away sooner or later, as will be more fully explained hereinafter, and likewise the hubs of the rollers wear, so that the rollers themselves, instead of continuing vertical or nearly so, dip toward the center of the machine, thus wearing the bottom plates still further at one point. When the rollers and plates wear in such shape, the sand cannot be mixed and ground properly, because there are only a few points of contact between rollers and plates, and besides there is not enough of the sliding, horizontal motion between rollers and plates which is most desirable to mix and rub the various ingredients composing the mixture, in order to produce the best quality of sand, especially for foundry purposes.

The object of my present invention is to reduce expense due to the replacement of worn-out parts, and to produce a better and more uniform quality of product, such as sand.

With these several objects in view, my invention consists in rollers, and plates having recesses therein adapted to receive an accumulation of sand which becomes compact and hard, automatically renewing and replacing the wear on the sand, thus increasing the efficiency of these parts, and thus greatly prolonging their life.

My invention further consists in certain novel features of construction and combinations of parts, which will be hereinafter fully described and pointed out in the claims.

In the accompanying drawings: Figure 1 is a view in side elevation showing the type of a grinding machine now commonly in use, with dotted lines indicating the wear which commonly takes place on the peripheries of the rollers, and in the bottoms of the pans, Fig. 2 is a similar view of my improved machine, Fig. 3 is an end view of one of the rollers, Fig. 4 is a transverse vertical section through the same, Fig. 5 is a plan view of the pan, showing several of the removable plates in the bottom thereof, Fig. 6 shows a modified form of plate having grooves instead of holes, Fig. 7 is a cross section through this modified form of plate, and Figs. 8 and 9 are similar sectional views showing other forms that can be given the holes or grooves.

In the construction illustrated in Fig. 1, I have attempted to illustrate the wear which takes place in the machine of this character now in general use. In almost every instance, the wear to the rollers takes place as shown in dotted lines in W—W, and the wear to the removable plates B, B, occurs somewhat as shown in dotted lines V—V. The hubs of the rollers wear so that the latter instead of running vertically or nearly so, dip toward the center of the machine, wearing the bottoms of the plates B, B, still further toward the center as also illustrated by the dotted lines V—V.

In the machine used to illustrate my invention, a vertical shaft 1 is stepped at 2 on the base 3 of the frame. This shaft carries the pan 4. The shaft 1 is supported by a beam 5, surmounting the pillars or uprights 6, 6. The drive shaft 7 is journaled in boxes 8, 8, on the beam 5, and gears 9, and 10 transmit motion from the horizontal drive shaft 7 to the vertical shaft 1. Rollers 11, 11, have their hubs 12, 12, journaled in bearings 13, 13, on the inner faces of the pillars or uprights 6, 6.

Referring now to the pan 4, and more particularly the removable plates 14, 14, which form the bottom thereof, these are of the usual segmental form, as shown in Fig. 5, and are conveniently held in place by screws 15, 15. These plates are provided with holes 16, 16, and grooves 17, 17, as illustrated in Figs. 5, 6, and 7; and different forms which these holes and grooves may take are illustrated in Figs. 7, 8 and 9. The rims of the rollers are circumferentially grooved as at 18, 18, and the transverse shape of these grooves might vary likewise, as illustrated in Figs. 7, 8, and 9, the object of these grooves in the rollers and the holes in the plates being that they retain the sand as illustrated. The sand used in foundries has a certain strength, and it will stick so hard in these grooves and holes that it becomes almost as hard as a rock, and forms thereby a roller or plate, the wearing surface of which is mostly sand, and it is plainly seen that in a roller or plate so constructed, the portions which will tend to wear most are the projecting ridges or points of sand, which cost nothing and renew themselves indefinitely. In other words, the advantages of such roller and pan-plate construction are:—less wear, consequently less expense in renewing worn-out parts, and less time lost as a result of shutting down the sand grinders for repairs. The quality of the work is more uniform with these rollers than with the old style, because the original working conditions are preserved for a much longer period; and where porosity of the sand is advantageous, these rollers and plates will give better results because they do not crush the sand so fine. If the holes or corrugations are made close together, instead of ridges of sand, the whole surface will knit together, and the entire wearing surface could be made of sand.

As shown in Fig. 4, my preferred form of roller is cored out inside as at 20, although this is not an essential feature in every instance, as the weight of the roller must be proportioned to its width, and the kind of grinding to be done. I prefer to core out the roller because it affords an opportunity of balancing the roller so that under ordinary working conditions, it will remain straight or nearly so, preserving thereby the original working condition of the new machine. The side 21 being thicker than the side 22, the weight on the side 21 will be greater, and the heavier and thicker side will be so mounted that it will be toward the outside.

I have found in practice that my rollers last several times as long as the ordinary rollers made from the same quality of metal, but I have likewise found that the hubs of my rollers were the weakest point, and

tended to wear out long before the face. Consequently I provide the rollers with removable hard steel bushings 23, held fast by means of babbitt or spelter filling 24 cast between the hub of the roller and the bushing. Thus the worn-out bushing may be readily removed by heating it with a torch sufficiently to melt the spelter, and the bushing can be replaced by a new one.

I am aware that some grinding pans are not, or cannot be equipped with removable plates. In this case, I make the inside or bottoms of the pans themselves with holes or grooves so as to obtain the same results as with the removable plates. Also some machines might employ one of my rollers in connection with a plain roller of the old type.

I do not care to confine myself to the use of rollers and detachable pan-plates for foundry purposes only, as the same principle would apply equally to any grinding machinery whatever, whether it is used for grinding sand, rock, chemicals, or what not. It is also evident that more or less slight changes might be resorted to in the form and arrangement of the several parts described without departure from the spirit and scope of my invention, and hence I do not wish to be limited to the exact construction herein set forth, but:

Having fully described my invention, what I claim as new and desire to secure by Letters Patent, is:—

1. A grinding-machine comprising a pan and a roller mounted to work in connection with said pan in such a manner that a sliding horizontal motion takes place between the two, and said roller provided with circumferential grooves in which the material being ground is packed and held.

2. A grinding-machine comprising a grinding face having recesses therein, and a rotary grinding member mounted to have sliding horizontal motion over said grinding face and provided with circumferential grooves in its working face, said recesses and grooves formed and disposed to receive and hold the material being ground.

3. A grinding-machine comprising a pan and a roller mounted in such a manner that in its passage over the pan a sliding horizontal grinding motion takes place between the two, said pan having recesses in the face thereof, and grooves formed circumferentially on the face of the roller, said recesses adapted to receive and hold the material being ground.

4. A grinding machine, comprising a pan and a roller, said roller mounted to travel over the face of the pan in such a manner that a sliding horizontal grinding action takes place between the two, said pan having recesses in the face thereof, grooves formed circumferentially around the roller,

said recesses and grooves so formed that the material being ground is received and held therein to form a grinding surface, and means for transmitting movement to 5 one of said grinding members, whereby the roller will be caused to come in contact with the pan.

5. A grinding machine, comprising a pan mounted to be capable of rotation, a roller 10 revolvably mounted adjacent the pan and at right angles to the axis of rotation of the pan, said pan having recesses in the face thereof, grooves formed circumferentially in the roller, said recesses and grooves constructed to receive and hold the material being ground for forming a grinding surface, and means for rotating the pan, which, 15 through the engagement of the material being treated with the roller, causes the roller to revolve and transmits a sliding horizontal grinding motion to the material in the pan.

6. A grinding machine, comprising a pan

mounted to be capable of rotation, rollers 25 revolvably mounted adjacent the pan and at right angles to the axis of rotation of the pan, said pan having recesses in the face thereof, grooves formed circumferentially in the rollers, said recesses and grooves constructed to receive and hold the material 30 being ground for forming a grinding surface, and means for rotating the pan, which, through the engagement of the material being treated with the rollers, causes the rollers to revolve and transmits a sliding horizontal 35 grinding motion to the material in the pan, said rollers made heavier on their one side, so that they will bear more evenly against the working face of the pan.

In testimony whereof I affix my signature, 40 in the presence of two witnesses.

JACQUES MORAT.
